CLAIM

The ornamental design for a catheter handle, as shown and described.

DESCRIPTION

FIG. 1 is a top front perspective view of a catheter handle, showing our new design;

FIG. 2 is a bottom front perspective view of the catheter handle of FIG. 1;

FIG. 3 is a top side view of the catheter handle of FIG. 1;

FIG. 4 is a bottom side view of the catheter handle of FIG. 1;

FIG. 5 is a right side view of the catheter handle of FIG. 1;

FIG. 6 is a left side view of the catheter handle of FIG. 1;

FIG. 7 is a front side view of the catheter handle of FIG. 1; and,

FIG. 8 is a rear side view of the catheter handle of FIG. 1. Those portions shown in broken lines are for illustrative purposes only and form no part of the claimed design.
